PUMP

August M. Hamer, Liberty, Tex.

Application October 19, 1943, Serial No. 506,908

8 Claims. (Cl. 103—46)

This invention relates to a pump.

An object of the invention is to provide a pump of the character described specially designed for use in deep wells such as oil wells.

Another object of the invention is to provide a pump of the character described operable upon intake, or up, stroke by the pressure of an operating liquid and upon downstroke by the weight of the column of liquid being pumped from the well.

A further object of the invention is to provide a pump of the character described having a pumping cylinder and a pumping plunger therein with means for applying the pressure of an operating liquid to the plunger to effect an upward, or intake, stroke to the plunger whereby the pumped liquid will be drawn in to the cylinder from the well with a valve, arranged to be opened at the end of the intake stroke whereby the liquid drawn into the cylinder will be forced out of the cylinder, upon down stroke of the plunger, and upwardly through the pump tubing to the ground surface.

A further object is to provide in a pump of the character described a novel valve construction which will be automatically opened when the plunger reaches the limit of its upward movement to allow the discharge of the liquid drawn into the cylinder upon the preceding upstroke of the plunger and which will be automatically closed when the plunger reaches the limit of its downward movement whereby the pressure of the operating liquid will be applied to the plunger to effect the succeeding upward, or intake, stroke.

By the use of the construction hereinafter described all pump operating sucker rods will be dispensed with.

With the above and other objects in view the invention has particular relation to certain novel features of construction, operation and arrangement of parts an example of which is given in this specification and illustrated in the accompanying drawings, wherein—

Figures 1, 2 and 3 show vertical sectional views of the upper, intermediate and lower sections, respectively, of the pump shown on down, or discharge, stroke.

Figures 4 and 5 show vertical sectional views of upper and intermediate sections, respectively, of the pump showing the plunger on up, or intake, stroke, and

Figure 6 shows a side elevation of the complete pump shown partly in section.

Referring now more particularly to the drawings wherein like numerals of reference design-

ate the same parts in each of the figures the numeral 1 designates the well casing and the numeral 2 designates the well tubing, both casing and tubing leading to the ground surface.

5 Connected to the lower end of the tubing there is the pumping cylinder 3 having one or more inlet openings 4 for the operating liquid.

Connected to the lower end of the pump cylinder there is a coupling 5 having an inside 10 downwardly tapering seat 6 and connected to this coupling and extended down into the well there may be the usual well screen 7 whose upper end is packed off from the casing by a conventional packer 8.

15 Within the pumping cylinder 3 there is a plunger having the upper and lower plunger heads designated generally by the numerals 9 and 10 and which are connected by the tubular plunger body 11 having one or more inlets 12 for the operating liquid. The upper and lower plunger heads are formed by the downwardly opening cup rings 13 and the upwardly opening cup rings 14 which are separated by the respective spacers 15 and 16 suitably secured, in assembled relation, 20 on the plunger body as shown.

The plunger body 11 forms, in effect, a cylinder and fitted closely within the cylinder beneath the inlets 12 there is a packing assembly formed of the upwardly opening cup rings 17 and the intervening spacers 18 which are secured on the upper end of the flow tube 19 by means of upper and lower collars 20 and 21.

The lower end of the flow tube 19 is screwed into the gland 22 which in turn is screwed into 35 the upper end of the valve cage 23. This cage has a tubular inlet valve seat 24 therein which is controlled by the upwardly opening ball valve 25.

Beneath the valve cage 23 there is a lower valve 40 cage 26 and said cages are connected by the tubular coupling 27. The lower valve cage 26 has the tubular inlet valve seat 28 controlled by the upwardly opening ball valve 29 and screwed into the lower end of the valve cage 26 there is a tubular anchor 30 which is downwardly tapering 45 externally and fitted into the seat 6. This anchor has a surrounding seal 31 forming a fluid tight joint with said seat.

Accordingly the flow tube 19, the packing assembly, on the upper end thereof, and the valve assembly, at the lower end thereof, are anchored in place and the pumping plunger moves up and down relative thereto.

Extending axially through the upper plunger head 9 there is a sleeve valve 32 whose lower end

may be closed by the downwardly elongated plug 33. The valve is provided with a series of inlet ports 34 located near the lower end of the valve. A seal ring 35 is installed within the plunger body 11 at the lower end of the head 9 and through which the valve is fitted. The valve has a surrounding expandable ring 36 seated in an annular groove 37 therearound. This ring may seat in the upper or lower inside annular grooves 38 or 39 within the plunger body to hold the valve in its upper or lower position relative to the plunger. As shown in Figure 1 it is in said lower position and as shown in Figure 4 it is in its upper position.

When the valve is in its upper position operating liquid entering the cylinder 11 will force the pumping plunger upwardly but when the valve is in its lower position the pumped liquid may escape from the cylinder 3 up through the flow tube 19 through the ports 34 on up through the valve 32 and the tubing 2 to the ground surface.

Operating liquid may be forced down through the well casing under constant pressure and will enter through the openings 4, as indicated by the arrows in Figure 2, between the upper and lower plunger heads 9 and 10. With the pumping plunger in its lower position, as indicated in Figures 4 and 5, this operating fluid will enter through the ports 12 between the seal 17 beneath and the seal 35 above. The ports 34 will now be closed to the operating fluid and the pressure thereof confined between the seals, or cup rings, 17 beneath and the seal 35 above will operate to move the pumping plunger upwardly in the direction indicated by the arrows in Figures 4 and 5 thus drawing in a charge of well liquid from the well beneath past the valve 29 and out through the open cage 26 and into the lower end of the cylinder 3 beneath the plunger. The pressure of this operating liquid will hold the valve 25 closed. As the plunger approaches the limit of its upward movement the upper end of the valve 32 will contact against the cross rod 40 in the tubing above. This will stop the upward movement of the valve but pressure of the operating liquid will continue the upward movement of the plunger and the expandable ring 36 will be contracted and unseated from the groove 38 and as the plunger moves on upwardly the groove 39 will register with said ring 36 and the ring will expand and snap into the groove 39. In the meantime the seal ring 35 will have moved above the ports 34 of the valve and the pressure of the operating fluid will be relieved through said ports and the pumping plunger will move downwardly by force of gravity assisted by the weight of the column of fluid in the tubing 2. As the plunger moves on down the pumped liquid in the cylinder beneath will be forced out of said cylinder passing in through the cage 26 and up past the valve 25 and on up through the flow tube 19, as indicated by the arrows in Figures 2 and 3, and will enter the cylindrical plunger body 11 and will pass on up around the valve 32 and through the ports 34 thereof and on up through the tubing 2. As the plunger approaches the limit of its downward movement the lower end of the valve plug 33 will contact against the upper end of the flow tube 19 and this will stop the downward movement of the valve. The plunger however will continue its downward movement and unseat the ring 36 from the groove 39 and when the groove 38 registers with said ring the ring will expand and snap into said groove and meanwhile the seal ring 35 will have

moved downwardly beneath the valve ports 34, thus completing the cycle and thereupon the plunger will begin another up stroke, or intake stroke, to draw in an additional charge of liquid from the well; and to elevate the column of pumped fluid in the tubing 2 above.

It is to be understood that the pump will be located in the well beneath the level of the well liquid.

10 The column of operating liquid in the casing 1, as well as the column of pumped liquid in the tubing 2, extend to the ground surface and approximately balance each other therefore a comparatively low pressure may be applied to the operating fluid in order to over balance the column of pumped liquid so that high pressure equipment will not be required.

15 The drawings and description are illustrative merely while the broad principle of the invention will be defined in the appended claims.

20 What I claim is:

25 1. A well pump comprising a discharge tubing, a cylinder carried thereby and having a side opening for operating liquid and having a valve controlled inlet opening, a tubular plunger in the cylinder having upper and lower seals with the cylinder above and beneath the side opening and having an inlet opening, a flow tube anchored in the cylinder and having an upwardly opening 30 valve controlling the flow of the pumped liquid therethrough from the cylinder, a seal between the flow tube and plunger, a sleeve valve within and mounted to move with the plunger and arranged to conduct liquid from said tube into the tubing above, said valve having a seal therearound with the plunger and having a side opening and means for moving the valve to carry the opening thereof above and beneath its seal as the plunger moves to lower and upper positions, respectively.

35 2. A well pump comprising a discharge tubing, a cylinder carried thereby and having a side opening for operating liquid and having a valve controlled inlet opening, a tubular plunger in the cylinder having upper and lower seals with the cylinder above and beneath the side opening and having inlet opening, a flow tube anchored in the cylinder and having a seal with the plunger 40 beneath said inlet opening and having an upwardly opening valve controlling the flow of the pumped liquid therethrough from the cylinder, a sleeve valve within and mounted to move with the plunger and arranged to conduct liquid from said tube into the tubing above, said valve having a seal therearound with the plunger and having a side opening and means for moving the valve to carry the opening thereof above and beneath its seal as the plunger moves to lower and upper positions, respectively.

45 3. A deep well pump comprising a tubing, a cylinder on the lower end of the tubing having an inlet port, a standing valve assembly controlling the inlet of well liquid into the cylinder, a flow tube anchored in the cylinder, an upwardly opening valve controlling the flow of liquid upwardly from the cylinder, through said tube, a tubular plunger body reciprocable over 50 said flow tube, upper and lower plunger heads on the plunger body on opposite sides of said port and forming seals with the cylinder, a seal on the flow tube with said plunger body, said body having an inlet port above the flow tube seal, a tubular sleeve valve arranged axially in, 55 and in sealed relation with, the plunger assembly

and having a side port and means to move the sleeve valve, as the plunger assembly reciprocates to carry the valve port above and beneath the valve seal whereby said sleeve valve will be closed and opened.

4. A deep well pump comprising a tubing, a cylinder on the lower end of the tubing having an inlet port, a standing valve assembly controlling the inlet of well liquid from the well beneath into the cylinder, a flow tube anchored in the cylinder, an upwardly opening valve controlling the flow of liquid upwardly through the flow tube, a plunger assembly in the cylinder including a tubular body and spaced plunger heads on the body in sealing contact with the cylinder and arranged on opposite sides of said port, said plunger body having a side inlet port between said plunger heads, sealing means on the flow tube forming a seal with the plunger body beneath the inlet port thereof, a tubular sleeve valve arranged axially in the upper plunger head and whose lower end is closed, sealing means in said upper plunger head forming a seal with said sleeve valve, said sleeve valve having an opening and means to move the sleeve valve, as the plunger assembly reciprocates, to carry the valve opening beneath and above the valve seal whereby said sleeve valve will be closed upon downward movement of the plunger assembly and opened upon upward movement of the plunger assembly.

5. A deep well pump comprising a tubing, an outer cylinder on the lower end of the tubing having an inlet port, a standing valve assembly controlling the inlet of well liquid into the cylinder, a flow tube anchored in the cylinder, an upwardly opening valve controlling the flow of liquid upwardly from the cylinder, through said tube, a tubular plunger body forming an inner cylinder and reciprocable over said flow tube, upper and lower plunger heads on the plunger body on opposite sides of said port and forming seals with the outer cylinder, sealing means on the tube forming a seal with said inner cylinder, said body having an inlet port above the flow tube seal, a tubular sleeve valve arranged axially in, and in sealed relation with, the plunger assembly and having a discharge port and means to move the sleeve valve, as the plunger assembly reciprocates, to carry the discharge port above and beneath the valve seal whereby said discharge port will be closed and opened.

6. A deep well pump comprising a tubing, an outer cylinder on the lower end of the tubing having an inlet port, a standing valve assembly controlling the inlet of well liquid from the well beneath into the cylinder, a flow tube anchored in the cylinder, an upwardly opening valve controlling the flow of liquid upwardly through the flow tube, a plunger assembly in the cylinder including a tubular body forming an inner cylinder and spaced plunger heads on the body in sealing contact with the outer cylinder and arranged on opposite sides of said port, said inner cylinder having a side inlet port between said plunger heads, lower sealing means on the flow tube forming a seal with the wall of the inner cylinder beneath the inlet port thereof, a tubular sleeve valve arranged axially in the upper plunger head and whose lower end is closed, upper sealing means in said upper plunger head forming a seal with

with said sleeve valve, said upper and lower sealing means forming a pressure chamber in the inner cylinder, said sleeve valve having a discharge opening and means to move the sleeve valve, as the plunger assembly reciprocates, to carry the valve opening beneath and above the valve seal whereby said opening will be closed to said chamber upon downward movement of the plunger assembly and opened to said chamber upon upward movement of the plunger assembly.

7. A deep well pump comprising a tubing, an outer cylinder on the lower end of the tubing having an inlet port, a standing valve assembly controlling the inlet of well liquid from the well beneath into the cylinder, a plunger assembly reciprocable in the cylinder including a tubular body forming an inner cylinder and spaced plunger heads on the body in sealing contact with the outer cylinder and arranged on opposite sides of said port, said inner cylinder having a side inlet port between said plunger heads, a flow tube in communication with the outer cylinder and extended into the inner cylinder, lower sealing means on the flow tube forming a seal with the wall of the inner cylinder, a tubular sleeve valve arranged axially in the upper plunger head and whose lower end is closed, upper sealing means in said upper plunger head forming a seal with said sleeve valve, said upper and lower sealing means forming a pressure chamber in the inner cylinder having an inlet port and into which the flow tube discharges, said sleeve valve having a discharge opening and means to move the sleeve valve, as the plunger assembly reciprocates, to carry the valve opening beneath and above the valve seal whereby said sleeve valve will be opened to said chamber upon upward movement of the plunger assembly.

8. A deep well pump comprising a tubing, an outer cylinder on the lower end of the tubing having an inlet port, a standing valve assembly controlling the inlet of well liquid from the well beneath into the cylinder, a plunger assembly reciprocable in the cylinder including a tubular body forming an inner cylinder and spaced plunger heads on the body in sealing contact with the outer cylinder and arranged on opposite sides of said port, said inner cylinder having a side inlet port between said plunger heads, a flow tube in communication with the outer cylinder and extended into the inner cylinder, lower sealing means on the flow tube forming a seal with the wall of the inner cylinder, a tubular sleeve valve arranged axially in the upper plunger head and whose lower end is closed, upper sealing means in said upper plunger head forming a seal with said sleeve valve, said upper and lower sealing means forming a pressure chamber in the inner cylinder having an inlet port and into which the flow tube discharges, said sleeve valve having a discharge opening and reasonable, interlocking means between the plunger assembly and sleeve valve to move the sleeve valve, as the plunger assembly reciprocates, to carry the valve opening beneath and above the valve seal whereby said sleeve valve will be opened to said chamber upon upward movement of the plunger assembly and closed to said chamber upon downward movement of the plunger assembly.
